Primary Examiner — John Windmuller*Assistant Examiner* — John R Yeh(74) *Attorney, Agent, or Firm* — Onello & Mello, LLP(57) **CLAIM**

An ornamental design for a loose material collection device, as shown and described.

DESCRIPTION

FIG. 1 is a top perspective view of an embodiment of a loose material collection device, in accordance with the present invention;

FIG. 2 is a plan view of the loose material collection device of FIG. 1;

FIG. 3 is a side elevation view of the loose material collection device of FIG. 1;

FIG. 4 is a left side view of the loose material collection device of FIG. 3;

FIG. 5 is a right side view of the loose material collection device of FIG. 3;

FIG. 6 is a bottom view of the loose material collection device of FIG. 1; and,

FIG. 7 is a bottom perspective view of the loose material collection device of FIG. 1.

The broken lines in FIGS. 1, 2, 3, 6, and 7 in the drawings indicate portions of the loose material collection device that form no part of the claimed design.

1 Claim, 2 Drawing Sheets(56)
